OPHTHALMIC SLIDE PROJECTOR

John T. Armbruster, Niagara Falls, N.Y., assignor to
American Optical Corporation, Southbridge, Mass., a
corporation of Delaware

Filed Mar. 28, 1969, Ser. No. 16,500

Term of patent 7 years

Int. Cl. D16—03

U.S. Cl. D61—1

Fig. 1

Fig. 2

Fig. 3

Fig. 4

Fig. 5

FIG. 1 is a front perspective of an ophthalmic slide projector showing my new design;

FIG. 2 is a top plan view of an ophthalmic slide projector shown in FIG. 1;

FIG. 3 is a rear elevational view thereof;

FIG. 4 is a front elevational view of an ophthalmic slide projector; and

FIG. 5 is a side elevational view of an ophthalmic slide projector shown in FIGS. 1, 2, 3 and 4, the opposite side not shown, being of substantially the same appearance.

I claim:

The ornamental design for an ophthalmic slide projector, substantially as shown.
